Fig. 6

FIGURE 6 is an elevational view of yet another modified container for oil products or the like wherein the columnar section includes an upper rib which is interrupted.

The characteristic features of our design are indicated by solid lines and reside in a series of ribs at least one of which is interrupted and one of which is continuous, a planar surface defined by said interrupted rib permitting placement of marks thereon. The top and bottom views for the containers of FIGURES 4, 5 and 6 are the same as those illustrated by FIGURES 2 and 3 and the opposite sides thereof not shown are the same as those illustrated.

We claim:

The ornamental design for a container for oil products or the like, substantially as shown and described.
